(57) CLAIM

An ornamental design for a footwear substantially as shown and described.

DESCRIPTION

FIG. 1 is a top front left side perspective view of a footwear; FIG. 2 is a top front right side perspective view thereof; FIG. 3 is a front elevation view thereof; FIG. 4 is a rear elevation view thereof; FIG. 5 is a left side elevation view thereof; FIG. 6 is a right side elevation thereof; and, FIG. 7 is a top plan view thereof.

The broken lines in the figures depict portions of a footwear which are not part of the claimed design.
